A. A. KRAMER

FAUCET

Filed June 9, 1922

Fig. 1.

Fig. 2.

INVENTOR
Andrew A. Kramer.
BY *Marie O'Donnell*
ATTORNEY

UNITED STATES PATENT OFFICE.

ANDREW A. KRAMER, OF KANSAS CITY, MISSOURI.

FAUCET.

Application filed June 9, 1922. Serial No. 567,152.

To all whom it may concern:

Be it known that I, ANDREW A. KRAMER, a citizen of the United States, residing at Kansas City, in the county of Jackson and

5 State of Missouri, have invented certain new and useful Improvements in Faucets; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to tank faucets and the primary object thereof is to provide means whereby liability of leaks tending to cause fires will be reduced to a minimum.

It is recognized that the ordinary tank 20 faucet is liable to leak and the drippings sometimes catch fire. Since the fire will cause the flame in the vicinity of the tank faucet valve, it becomes necessary to use some separate means for cutting off the flow 25 of liquid through the pipe line to which the faucet is connected.

The pipe lines for tanks have their receiving ends communicating with the discharge port in the tank. The discharge 30 ports in the tank are usually provided with valve seats so that normally unseated valves can be tripped to move into seating position and thus shut off communication between the tank and the pipe. Therefore, the contents of the tank will not flow from the pipe 35 even though there is a leak in the delivery faucet or in the event that the faucets should be open during the time that the fire is occurring.

40 The difficulty with such a construction is that it is not always convenient to climb to the top of the tank to trip the valves so I have eliminated the difficulty by providing an auxiliary valve so co-related with the 45 operating mechanism for the faucet that it will move into closing position when the faucet valve is moving into closing position and open when the faucet valve is in unseating position. There is a positive connection 50 between the auxiliary valve and the faucet valve operating mechanism so that the movements of the valves must synchronize and thereby insure a positive closing action of the auxiliary valve whenever the operat-

ing mechanism for the faucet valve is in 55 closing position and inversely insure an opening movement of the auxiliary valve when the faucet operating mechanism is moved into open position.

The novel arrangement of the faucet and 60 auxiliary valve together with the connections between them will be apparent by reference to the following description in connection with the accompanying drawings, in which—

65 Fig. 1 is a view partly in elevation and partly in section through a tank, and through a dispensing pipe, showing the faucet and valve connected thereto and illustrated in elevation.

70 Fig. 2 is a vertical, longitudinal, sectional view through the dispensing pipe showing the faucet valve in elevation and the auxiliary valve in section.

75 Referring now to the drawings by numerals of reference:

1 designates a wagon tank having an oil dispensing chamber 2, it being understood that the tank may be divided into compartments to provide separate chambers, 80 each being equipped with a dispensing pipe line and a faucet. The dispensing pipe 3 communicates with the tank through a discharge orifice 4 in the tank. This orifice is usually supplied with a safety valve normally unseated but which may be tripped from the top of the tank so that communication between the tank and the pipe 3 may be closed off in the case of emergency, but in my invention the valve is eliminated. 90

At the end of the pipe 3 is a dispensing faucet 5 provided with a valve seat 6, on which is a valve 7 having a stem 8 guided in the cap orifice 9, there being a spring 10 around the stem, one end of which may 95 bear against the valve and the other end against the cap 11.

This construction is not new nor is the lever 12 connected to the valve stem and mounted on a rock shaft 13 to be rocked 100 with the lever 12 new. Such faucets are well known.

In the pipe line 3, however, is arranged a valve casing 14, carrying a turning plug valve 15 with an orifice 16 which may be 105 caused to align with the channel of the pipe 3, as shown in Fig. 2. The end of the valve 15 is provided with a shaft 17, projecting

through the casing 16 and provided with a crank 18, at which one end of a link 19 is connected, the other end of the link being connected to a crank 20 controlled by the lever 12'.

When the operator grasps the lever 12' to move it into valve unseating position, the faucet valve 7 will be raised off its seat 6. There will be a pull exerted upon the link 19 so that the crank 18 will be swung to partially rotate the shaft 17 and cause the valve 15 to move into open position, as shown in Fig. 2. When the lever 12' is moved into valve closing position, however, the valve 7 will be seated and a rearward thrust will be imparted to the link 19, which will cause the valve 15 to close. Therefore, the valve 15 will close the pipe line every time the valve 7 is closed so that in the event that the faucet valve 7 tends to leak, the pipe will be closed to the tank in rear of the valve 15 and liability of fires occurring from drippings and the like will be eliminated.

What I claim and desire to secure by Letters Patent is:

The combination with a dispensing pipe line, of a valve casing in the pipe line, a rotatable valve plug in the casing having a through port, the plug having a stem extending through the casing, a faucet at the delivery end of the pipe line, the faucet having a valve seat, a spring pressed reciprocating valve in the faucet, normally urged upon the seat, the valve having a depending stem, a rock shaft in the faucet having an arm connected to the stem whereby when the rock shaft is operated in one direction, the valve will be lifted off its seat, a crank on the end of the first named valve stem, a crank on the rock shaft, a link connecting the two cranks and a lever on the rock shaft whereby when the lever is operated, the valve and plug will be moved in unison.

In testimony whereof I affix my signature.

ANDREW A. KRAMER.
